US00D757649S

(12) **United States Design Patent**
Pisharodi

(10) **Patent No.:** **US D757,649 S**
(45) **Date of Patent:** **** May 31, 2016**

(54) **ADAPTER**

(71) Applicant: **Madhavan Pisharodi**, Brownsville, TX (US)

(72) Inventor: **Madhavan Pisharodi**, Brownsville, TX (US)

(73) Assignee: **Perumala Corporation**, Brownsville, TX (US)

(**) Term: **14 Years**

(21) Appl. No.: **29/477,067**

(22) Filed: **Dec. 19, 2013**

(51) **LOC (10) Cl.** **13-02**

(52) **U.S. Cl.**

USPC **D13/110**; D13/107

(58) **Field of Classification Search**

USPC D13/107, 108, 109, 110, 111, 118, 147, D13/153; 320/130–135, 148–150, 155; D10/46, 70, 74

CPC H02J 7/02

(57) **CLAIM**

The ornamental design for an adapter, as shown and described.

DESCRIPTION

FIG. 1 is a perspective view of an adapter showing my new design; and,

FIG. 2 is a perspective view of a second embodiment of an adapter showing my new design.

The broken lines form no part of the claimed design.

1 Claim, 2 Drawing Sheets
